UNITED STATES PATENT OFFICE.

WILLIAM B. WARING, OF BRONX, NEW YORK.

AMUSEMENT APPARATUS.

Application filed February 12, 1927. Serial No. 167,758.

My invention relates generally to amusement apparatus, and more particularly to the type such as is used in amusement parks, resorts, and like places, wherein a number of 5 players participate.

The primary object of the invention resides in the provision of an amusement device which is both new in the line of attraction, and which employs certain natural or 10 physics principles which are radically new in apparatus of this character.

Another object resides in so constructing my improved device as to utilize this new principle in the form of a race, wherein a 15 series of horizontally disposed shafts, rotated at similar speeds, are each provided with a loose collar or disk having a central opening of larger diameter than that of said shafts, which permits the inertia from rotation to cause various changes of plane of the respective disks which effects "creeping" or movement thereof in a forward or reverse direction along the shafts at varied speeds in ratio with the degree or angle of 20 deflection of the disks in either direction, which results in at least one disk traversing a prescribed course in advance of the remainder of disks, consequently winning the race and thereby entitling an award to the 25 particular participant to which said individual disk was assigned.

Another object resides in so constructing the device that the same cannot be fraudulently manipulated by the operator in charge 30 of the race in an endeavor to favor any particular participant, and which object is augmented by the open construction wherein the parts are visible to participants at all times, and eliminates the possibility of such 35 tampering.

A further object resides in the provision of an entirely automatic amusement device wherein it is only necessary to press a single button, and the mechanism operates to 40 accomplish the running of the race, the announcing of the winner, and the return of parts to a normal idle position, in readiness for another operation; thus obviating the necessity of separate manual controls for 45 these various phases of operation.

Still further objects reside in simplicity of construction coincident with the manifold operations effected, simplicity of manipula-

tion, positive action, and which is inexpensive of manufacture and highly amusing and 55 efficient for the purposes intended.

With these and other objects in view, the invention resides in certain novel construction, and combination and arrangements of parts, the essential features of which are 60 hereinafter fully described, are particularly pointed out in the appended claims, and are illustrated in the accompanying drawings, in which

Figure 1 is a top plan view of my improved amusement apparatus;

Figure 2 is a vertical central longitudinal sectional view therethrough, taken on the line 2—2 of Fig. 1;

Figure 3 is a vertical transverse sectional view taken on line 3—3 of Fig. 2;

Figure 4 is a rear elevation;

Figures 5, 6, and 7 are detail views of certain of the electrical units, and

Figure 8 is a wiring diagram illustrating 75 the connection of the various electrical units with the source of electrical energy;

Figure 9 is a fragmentary vertical sectional view of a modified driving means.

Referring more particularly to the drawings, the reference character 10 designates a base from which rise front and rear uprights 11 and 12 respectively, both of which support a series of bearing members 13 provided with cap bearings 14 for a plurality of 80 rotatable shafts 15. Said shafts are preferably tubular for lightness and rigidity, and the same are provided at their rear extremities with fixed gears 16, each of which meshes with the next adjacent gear to establish a train.

The central gear of said train meshes with an underlying pinion 17 on the armature shaft of an electric motor 18 which in turn imparts rotation to the respective gears 95 16 to rotate the shafts 15. Loosely mounted on each of said shafts is a washer or disk 19 which is provided with a central opening 20 of larger diameter than the diameter of said shaft, for permitting inertia from rotation to cause various changes of plane of the respective disks which in turn effects "creeping" or movement thereof in a forward or reverse direction along said shafts at varied speeds in ratio with the angle or 100 degree of their deflection in either direction.

From the description thus far it will be seen that during the running of the motor 18, rotation will be imparted to the shafts 15 through the medium of the gears 16 and 17, to impart a free rotation of the disks 19 and cause the same to creep or move longitudinally along the shafts by reason of the action previously set forth.

It is the object of the present device to utilize this action in the form of a race by positioning the disks in a starting position adjacent the front ends of the shafts in transverse alignment, and then operating the motor to cause the disks to traverse the shafts until they abut a rear contact element 21 which reverses their direction of longitudinal movement along said shafts and simultaneously sets a circuit in condition, as hereinafter set forth, to annunciate the first disk to arrive at the front end of the shaft, when the same actuates a second contact element 22 at the front end of said shafts. In actual use it has been found that at least one disk of the series will move to the back end of the shaft, set the circuit and then move to the front end, completing said circuit to operate annunciator 25 in a period of approximately one-half minute, which renders the device highly practicable for use in amusement parks and resorts, where it is imperative to run off the races rapidly to accommodate large numbers of participants.

The disks 19 are provided with suitable indicia or a numeral as designated at A, corresponding to a similar numeral indicated by B on a counter 23 positioned at the front of an amusement stand or booth 24 in which my improved device may be mounted, and persons participating in the race stand before said counter 23 and place a marker on the numeral directly in front of them, which designates the disk they choose to win the race in the manner set forth.

The annunciators 25 are electrically connected with the respective contact elements 21 and 22 in such a manner that should any of the disks move from a starting position to the front contact element 22 before tripping the rear contact 21, the annunciator will not operate, until such disks have first tripped said rear element 21 to set a circuit, in a manner hereinafter set forth, after which said front contact element 22 is in condition to effect the operation of the annunciators 25.

Simultaneous to the operation or dropping of any of the annunciators 25, the electrical circuit to the motor 18 is opened to cause the same to stop at the completion of the race. As certain of the disks 19 will be left in various positions along their respective shafts upon such stopping of the motor 18, I provide automatic means for bringing these "straggler" disks into an aligned starting position simultaneous to the opening of

said motor circuit. Such automatic disk-returning means comprises an auxiliary motor 26 provided with a pinion gear 27 in meshing engagement with an idler gear 28 which in turn meshes with a gear 29 on a worm shaft 30 to rotate same during running of said auxiliary motor 26. A transverse travelling frame 31 normally rests adjacent the rear series of bearing members 13 and said frame is provided with a threaded bore 32 for coaction with the worm shaft 30 which causes movement of said frame therealong in a forward or reverse direction in a manner also described hereinafter. The transverse frame 31 is provided with upright U shaped fork members 33 which are adapted to engage the disks 19 to move same along their respective shafts to a starting position when said frame is moved from its normal rear position to the front by means of the motor and worm shaft just described.

When said transverse frame has moved a sufficient distance toward the front to place the disks in a starting position, the auxiliary motor is cut off, whereupon the same will start again in a reverse direction after having reached a substantially full stop. As will be appreciated this automatic action will return the frame to its normal idle position out of the path of movement of the disks 19, in a manner to be explained.

The transverse frame rides on a pair of guide rails 34 supported by the outer end pairs of bearing member 13. Said guide rails serve to hold the frame in alignment during its movement along the worm shaft 30 as set forth.

The various automatic means hereinbefore referred to are controlled and operated in the manner set forth in the following description and with particular reference to the wiring diagram illustrated in Figure 8 of the drawings.

A single spring contact pushbutton 35 need only be touched once when it is desired to start a race, as all the operations previously mentioned are thence carried out automatically and the device shuts itself off upon the completion of such operations. The apparatus is then in condition for another race, whereupon it is merely necessary, when desired, to push said button 35 to effect the running of a succeeding race. A wire 36 comprises one half of the pushbutton circuit 37 and said wire is connected to one terminal of the motor 18 and from the other terminal thereof, passes through the contact arm 38 of a solenoid-controlled switch 39 to negative or minus side of a battery or other suitable source of electrical energy 40 by way of a wire 41. A wire 42 constituting the other half of the circuit 37, passes through the solenoid 45, of a tandem solenoid switch 46, wherefrom said wire 42 passes to a contact 47 which effects a connec-

tion, by means of a contact bridge 48, to a second contact 47' from which a wire 42' is connected through a contact 49 and wires 42'' and 50 to the positive or plus side of the battery 40 through a main control switch 51. When this circuit 37 is closed, the solenoid 45 is momentarily energized to move the conductor bridge 48 away from the contacts 47 and 47' to break the circuit through 50 said solenoid 45. Said movement of the switch 46 simultaneously moves a second bridge 52 into engagement with the contacts 49 and 53 to close the circuit to the motor 18 and the same operates the shafts 15 and disks 19 in the manner set forth to effect the running of the race.

Said motor 18 will continue to run until one of the disks 19 first sets the contact elements 21 and 22 in the following manner. 20 These contact elements comprise a fibre or insulating disk 54 fixedly mounted upon the cap bearings 14 and provided with central openings 55 sufficiently larger than the shafts 15 to permit the shafts to freely pass there- 25 through. Outwardly sprung hair-spring strips 56 are fixedly secured at their outer ends adjacent the peripheries of said disks 54, while the inner, outwardly projecting ends of said hair springs 56 are slightly spaced 30 from contact points 57 which they are adapted to engage when one of the sliding disks 19 abuts said springs. These spring contacts are radially arranged on the inner faces of 35 the front and rear series of disks in such manner that the travelling disks 19 will engage at least one set, spring 56 and contact 57, irrespective of the angle at which said moving disk strikes the springs. When this 40 occurs against the rear contact element 21 it closes a circuit 58 composed of main lead wires 59 and 60, the former of which passes through the coil of an electromagnet 61 and thence to the plus side of the battery 40 via the wire 50. The other lead 60 of the circuit 45 58, passes, by way of wire 62, contact arm 38 and wire 41, to the minus side of said battery to complete the circuit which, as will be appreciated, energizes the magnet 61, whereupon one end of an insulated arm 63 is 50 rocked about its pivot 64 to cause the other end thereof to bridge contacts 65 and 65' by means of a contact strip 66 carried thereby, as indicated in dotted lines in said Figure 8 of the drawings.

55 When said contact strip 66 bridges said contacts 65 and 65', a circuit 67 is in condition to be closed by contact of one of the disks 19 with the contact element 22, which is identical in construction to the element 21 60 previously described and like reference characters denote corresponding parts throughout the series of units illustrated and described.

When the first travelling disk 19 forces 65 one of the strips 56 of said contact element 22

into engagement with any of its various contacts 57, the circuit 67 is closed to accomplish the functions disclosed in the following.

A wire 68 comprises one half of said circuit and is normally incomplete due to the gap between said contacts 65 and 65', and said wire 68 passes through a magnet 69, contact points 70 and 71, bridged by a conducting strip 72, and thence through wires 73, 74, 62, contact arm 38 and wire 41 to the minus 75 side of the battery 40. The other wire 75 of said circuit 67, connects, through wires 76, 59, and 50, to plus side of the battery via the main control switch 51.

When such circuit 67 is closed by one of the disks 19, the magnet 69 is energized to draw the armature 77 into engagement therewith to rock an insulated bell crank annunciator lever 78 about its pivot 79 to draw the arm 80 thereof to a vertical position to expose a numeral thereon which corresponds to that of the winning disk. Said magnet is energized only momentarily as the same breaks its controlling circuit when the conducting strip 72 moves away from the contacts 70 and 71 which leaves the circuit 67 open by reason of the break in the wire 68.

The now horizontal arm 81 of the annunciator 78 brings a contact bridge 82 into engagement with contacts 83 and 84. These sets of contacts in the various annunciators are so arranged that any one of said annunciators will complete the main circuit 85 now to be described. One wire 86 of said circuit connects, as do all of the wires 86 of the series of annunciators, with a common lead 87, and which passes through contact 88, arm 38, contact 89, and wire 90 to one solenoid 91 of the tandem solenoid switch 39 and thence via wires 91', 92, and 41 to the minus side of said battery 40. The other wire 94 of said circuit 85, leads from the other contact 84 to a similar common main lead wire 95 which is in connection with the series of contacts 84, and said wire 100 is connected with a lead 96 which completes the circuit to the plus side of the battery 40 through wire 50 and switch 51.

The closing of this circuit 85, by the dropping of any of the annunciators 78, energizes the solenoid 91 of the switch 39, to draw the contact arm 38 away from the contacts 88 and 89 to break the momentary pull of said solenoid. This pull or movement of said arm 38 away from the contacts 88 and 89, breaks, and renders idle, all the circuits and electrically operated units just described, including the solenoid 91 itself, and by reason of said arm moving to a position to bridge contacts 97 and 98, a circuit 99 is closed to cause the sounding of an audible signal or bell 100.

From the description thus far it will be seen that when any of the disks 19 have tripped first the contact element 21 and then

actuated the similar member 22, such winning disk is automatically annunciated, and current supply cut off to prevent further annunciation in the event that a second disk 5 engages the contact element 22 afterward; a signal is set into operation, and the main motor 18 shut off.

Simultaneous to the energizing of the solenoid 91 to accomplish the above functions, the contact arm 38 bridges the contacts 97 and 98 to start the operation of the auxiliary or return-motor 26, as well as additional functions now to be explained.

The starting of said auxiliary motor 26 15 is effected by the movement of said contact arm which bridges said contacts 97 and 98 and energizes the magnet 101 of a dual magnet switch 102. The electrical circuit controlling said switch, includes a wire 103 20 which connects with the wire 99' of the bell circuit, and terminates at the contact 97. The other wire 104 conducts current through a contact 105, conducting arm 106 of the switch 102, and contact 107, wherefrom said 25 wire 104 connects through wires 95, 96, 50, and switch 51 to the plus side of the battery 40. The circuit is completed, to said magnet 101, through contact 98, and wires 108, 92, and 41, the latter of which effects 30 the connection to the minus side of said battery 40 when said contact arm 38 bridges the contacts 97 and 98. As will be seen, this action energizes said magnet 101 to bring the switch arm 106 into engagement with 35 the contacts 110 and 111 to bridge same.

A wire 112 leads from the contact 110 to the contact A of a tandem-solenoid polarity switch 113. Another wire 114 leads from the terminal 115 of the motor 26 to the pivot 40 116 of a conducting lever 117 which, in the position shown in full lines in Fig. 8, effects a connection between said wires 112 and 114 45 to establish one half of the circuit to said motor 26 via said switch arm 106, contact 111 and wires 118, 96, and 50 to the plus side of the battery 40. The connection from the terminal 119 of the motor 26 to the minus side of the battery is effected through the wire 120, which, like the wire 114, is connected to the pivot 121 of a similar lever 50 122 which connects, in the full line position, to a contact B wherefrom a wire 123 leads to said minus side of the battery 40 via its connection through wires 92 and 41. Therefore it will be seen that the motor 26 will be 55 thrown into operation in a forward direction by reason of the action of the magnet 101 and solenoid 91 of the switch 39.

The pole-changer or polarity switch 113, 60 comprises forward and reverse throw solenoids 124 and 125 provided with a common sliding arm or core 126 pivoted as at 127 and 128 to the respective levers 117 and 122 to throw the free ends of the same simultaneously to bridge the contacts A-B when the

solenoid 124 is energized, or to bridge the contacts A-C upon energizing of the solenoid 125 to deliver current to the motor 26 in a reverse direction in the usual well-known manner and which is deemed unnecessary to further describe.

The motor 26, as stated, will now be operating in a forward direction and return the disks 19 to their starting position by means of the fork-carrying transverse frame 75 31 and at which position a T-shaped contact element 129 carried thereby, bridges contacts 130 and 131. A wire 132 leads from contact 131 through the solenoid 125 of the polarity switch 113 and through the second 80 magnet 133 of the dual-magnetic switch 102, wherefrom said wire 132 connects, through wires 96, and 50, to the plus side of the battery 40. A second wire 134 leads from the contact 130 to the contact 97, and as the contact arm 38 is now bridging the contacts 97 and 98, as shown in dotted lines, current will flow from the minus side of the battery through wires 41, 92, and 108 and connect with the wire 134, and consequently energizes solenoid 125 which draws the core 126 and contact levers 117 and 122 into respective engagement with contacts C and A, and simultaneously energizes the magnet 133 90 of the switch 102 which moves the arm 106 95 back to the full line position to open the conduit 112 of the motor circuit and thus causing said motor 26 to stop. Said movement of the solenoid 125 which effects the bridging of the contacts A and C as illustrated in dotted lines, sets the circuit of the motor 26 in a condition to effect reverse rotation thereof upon the bridging of the contacts 110 and 111 in a manner now to be set forth.

Said motor 26 is provided with a current conducting T-bracket 135 fixedly secured to, and rotatable with, the armature shaft 136 of the motor, and which bracket is provided at its outer extremities with eyelets 137 for the pivotal connection of conductor arms 138 normally held in engagement with semi-circular contact segments 139 and 140 by a contractile spring 141 when the motor is idle. When the motor is in motion, however, said arms 138 will swing outwardly at their free ends, by reason of weights 142 thereon, and thereby be out of engagement with the contact segments 139 and 140 which latter are slightly spaced apart as at 143 115 just sufficient to isolate current therebetween but allow the thickness of the arms 138 to bridge the same in order that an electrical communication may be effected between said segments regardless of what position the arms 138 may come into engagement therewith.

To continue the description from the point where the transverse frame 31 had effected the cutting off of the motor 26 through the 130

medium of its contact element 129 engaging the contacts 130 and 131; it will be seen that since the motor had been running the conductor arms 138 were revolving in the dotted line position free from contact with the segments 139 and 140, but now that the motor has been shut off, it will be appreciated that the arms will gradually contract as the centrifugal action decreases with the slackening speed of rotation of the motor and that when the same has come to a substantially dead stop from running in a forward direction, it will immediately start in a reverse direction due to the movement of the polarity switch 113 having changed the polarity and by reason of contact of the arms 138 with the segments 139 and 140; it being remembered, however, that the arm 106 of the dual magnetic switch 102 is still in the full line position away from the contacts 110 and 111, and that the motor 26 has, therefore, not yet received its current to effect the reverse rotation now to be set forth.

One wire 92 leads from the segment 140 to the negative or minus side of the battery 40, while the other wire 144 connects with wire 108, wherefrom current is conducted through contact 98, arm 38, contact 97, wire 99' and 103 through magnet 101 of switch 102, and passes via contact 105, arm 106, contact 107 and wires 104, 95, 96 and 50 to the plus side of the battery to complete the electrical circuit through said semi-circular segments 139 and 140. When said circuit is closed by the arms 38 due to stopping of the motor 26, it will be seen that the magnet 101 is energized and again draws the switch arm 106 to a position to bridge the contacts 110 and 111, whereupon current is again delivered to the motor, but the same will start in a reverse direction by reason of the throwing of the polarity switch 113 as specified.

The object of the "governor" construction of the bracket 135 and arms 138, is to assure the motor 26 coming to a substantially full stop from forward running, before current can be delivered to effect running thereof in the opposite direction. This construction, therefore, eliminates the possibility of overheating or overloading the motor by simultaneously changing current from forward to a reverse direction.

Assuming the motor 26 is now operating in reverse, which rotates the worm shaft 30 in an opposite direction, it will be seen that the same will move the transverse frame 31 to the rear to its normal idle position, and at the same time move the contact member 129 away from contacts 130 and 131, breaking the various associated circuits, but which leaves all the units of said circuits in their respective set positions until returned as set forth hereinafter.

At a point slightly in advance of the completion of the rearward movement of

said frame 31, an automatic return, trip device 150 carried thereby, is actuated to return all the working parts to a normal idle position in the following manner.

The automatic return, trip device 150, 70 comprises insulated arms 151 pivotally connected to ears 152 provided on the frame 31. A cross link of current conducting material 153 is pivoted at its ends to said arms 151, and by reason of such connection of the link 153 with the arms, it will be seen that the link is free to move transversely while the link will remain parallel to the frame 31 at any position to which it may be swung, as will appear. Contact pins 154 serve as the pivotal connection of the link 153 to the arms 151, and said pins depend below the under face of the transverse frame 31 and are adapted to coact with angularly offset cams 155 mounted upon a 85 slightly inclined platform 156. Spring actuated ball contacts 157 and 158 are mounted within said cams 155 at one side thereof and are adapted to be engaged by the depending pins 154 upon the return movement of the frame 31, whereas it will be seen that said cams 155 will deflect the pins 154 away from the contacts 157 upon the forward movement of the frame 31. Contractile springs 159 are secured to the 90 said frame and to the arms 151 to normally hold same in the position shown but which allow the swinging movement of the link 153 and arms 151 when the pins 154 engage the cams 155. 95

A wire 160 constitutes one half of the circuit controlling said automatic return device 150, and said wire leads from one of the spring actuated ball contacts 157 to the plus side of the battery 40 by way of its connection through wires 95, 96, and 50, and through the main control switch 51. The other wire 161 passes through the solenoid 124 of the polarity switch 113, and the solenoid 162 of the tandem-solenoid switch 46, 105 wherefrom said wire 161 passes through the second solenoid 163 of the solenoid-controlled switch 39, and thence leads through the series of magnets 164 which effect the return of the annunciators 79 to the position shown. From said magnets 164, the lead 161 continues through the magnet series 165 controlling the return of the circuit-maker lever 63, and thence said lead 161 continues to the minus side of the battery 40 to complete the circuit to the automatic return device 150, via wires 92 and 41. 110

Therefore it will be seen that at a point slightly in advance of the completion of the rearward movement of the frame 31, the device 150 will complete the circuit just described, to momentarily energize and operate all of the solenoids and magnetic devices just mentioned to the full line positions due to the bridging of the contacts 157 115 120 125 130

and 158 by the pins 154 and conducting link 153.

As this energizing of the solenoid 163 draws the core 166 and arm 38 from the dotted line position to the full line position shown, it will be seen that during said movement, a momentary energizing of the magnet 133 will be effected due to the contact arm passing over contacts 167 and 168 to make the auxiliary circuit 169 to said magnet 133. This momentary energizing of said magnet 133, returns the arm 106 of the dual magnetic switch 102 to the full line position to open the circuit between the contacts 110 and 111 in order to leave the motor 26 in an idle position until the next race, as it will be seen that said motor 26 is cut off by the action of the device 150 just described, by reason of the energizing of the solenoid 124 of the polarity switch 113 which throws the levers 117 and 122 to the full line position to change the motor current from the wires 170 and 112, through the wires 112 and 123, but as the magnet 133 is simultaneously energized to open the gap between the wires 112 and 118 by reason of the arm 106 having moved away from the contacts 110 and 111, it will be appreciated that the motor 26 will consequently remain idle until another race or operation of the entire mechanism is effected.

The audible signal or bell 100 is also simultaneously cut off upon operation of the device 150, by reason of the contact arm 38 opening the circuit 99 thereof by moving out of bridging engagement with the contacts 97 and 98. Therefore it will be seen that the bell 100 rings from the moment a race is won, until the motor 26 and cross frame have moved the disks to a starting position, and then reversed and returned to their normal positions, whereupon ringing of said bell discontinues by reason of mechanism and operations set forth, after having rung a period of approximately twenty to thirty seconds; which period has been found most desirable in which to accomplish the full forward and reverse movements of the frame 31, to return the disks 19 to a starting position without "throwing" the same to such position at a high speed.

As previously set forth, the operation of the automatic-return device 150, energizes the solenoid 162 of the tandem solenoid switch 46 and which action moves the contact bridge 52 back to the position illustrated in Figure 8 to bridge the contacts 47 and 47' and render the solenoid 45 in condition to be again energized by the touching of the button 35, whereupon the entire apparatus will again operate in the manner set forth.

It will be seen that when necessary, magnets and solenoids are so wired as to automatically break their respective controlling

circuits immediately after being energized, in order to prevent waste of current and overheating which might result from the continuous flow of current therethrough.

It might be mentioned here that all of the units operate on a horizontal plane, except the motors 18 and 26 and annunciators 79, the former of which are upright, while the latter operate in a vertical plane.

As the motor 26 is cut off by the return of the transverse frame actuating the device 150 in the manner described, it will be seen that the simultaneous energizing of the solenoid 124 of the polarity switch, throws the same to a position to leave the motor circuit in a condition to operate said motor 26 in a forward direction, in its turn, during the running of a succeeding race or operation.

As it is desired to normally conceal the numerals on the wide front faces of the annunciator arms 80 until a race has been won, I provide shields 172 which are preferably black on their front faces and depend from pivots 173 to normally conceal said numerals on the annunciator arms 80. The pivots 173 of said shields 172 are in close proximity to the upper extremities of the levers 80 when the same are in the position illustrated in Figure 8. Therefore it will be appreciated that when one of the magnets 69 has been energized, the lever 80 will move to a vertical position, consequently swinging the shield 172 from a depending position to the horizontal position illustrated in Figure 6, which exposes the numeral on the lever 80 corresponding to the winning disk and to the numeral on the counter 23, thereby designating the winner of the race.

From the foregoing description it is believed to be clearly understood that I have provided an amusement apparatus which accomplishes all of the desired functions automatically, and which utilizes new principles in an efficient manner for the affording of a marked degree of amusement to both spectators and participants.

Although I have described what I deem the preferred embodiment of my invention which employs a motive power common to all the rotatable shafts, it may be found desirable in some instances to vary the driving means to allow each individual participant to operate the respective shafts, and such modified form of driving means is illustrated in Figure 9 of the drawings.

In said figure, the reference character 175 designates rotatable wheels disposed horizontally above the counter 23 of the booth 24. A knob 176 on each of the wheels is adapted to be grasped by the hand of a participant for imparting rotation to the wheel 175. Said wheels are keyed to vertical shafts 177 which are rotatably mounted within suitable bearings 178, and miter gears 179 keyed to

the lower ends of the shafts 177, mesh with similar gears 180 mounted on the front ends of horizontal shafts 181 disposed beneath the front aisle floor-boards 182 of the booth. A bevel gear 183 is keyed to the rear end of each shaft 181 and meshes with a bevel gear 184 on the lower end of each of the vertical shafts 185. Suitable bearings 186 and 187 rotatably support the respective shafts 181 and 185, and said latter shafts are provided with bevel gears 188 at the top thereof which mesh with similar gears 189 on the front ends of the shafts 15 previously described. Therefore it is deemed apparent that by this construction, a participant may rotate the particular shaft he desires, at any speed thought necessary, in an attempt to cause the disk thereon to complete the prescribed course, by rotating the wheel 175 which, through the medium of the gear connections set forth, will rotate all of the shafts mentioned.

It might be here stated that the push-button 35 is of the spring-return type utilizing a stationary strip contact 190 adapted to be engaged by a spring-strip contactor 191 when the button 192 is depressed, and upon release thereof, said spring-strip 191 will return to its normal position out of contact with the other strip 190. This type of push-button is utilized in order to obviate the necessity of the operator having to shut off the mechanism by additional manipulation of further controls, as the mechanism automatically shuts itself off and leaves the circuits in condition to operate again upon the touching of said push-button 35 in the manner herein set forth.

While I have described what I deem the preferred embodiments of my invention, it is obvious that many of the details of construction may be varied without in any way departing from the spirit of my invention, and I therefore do not limit myself to the exact details of construction shown, nor to anything less than the whole of my invention, limited only by the appended claims.

I claim:

1. Amusement apparatus comprising a series of horizontally disposed rotatable shafts, means for imparting rotation thereto, rotatable members loosely carried by said shafts and slidable longitudinally thereof, and trip members adjacent the ends of said shafts adapted to be operated by said rotatable sliding members substantially as, and for the purpose specified.

2. An amusement device of the character described comprising, in combination, a plurality of rotatable shafts, means for imparting rotation thereto, members loosely carried by said shafts and movable longitudinally thereof by inertia resulting from frictional contact of said disks with said rotatable shafts during rotation, and trip members

adapted to be engaged by the disks, and positioned adjacent the ends of said shafts, one of said trip members adapted to be actuated in advance of the other to set an electrical circuit in condition, whereupon actuation of said latter trip member will close said circuit to denote which of said disks traverses a prescribed course over said shafts in advance of the remainder of said disks, substantially as, and for the purpose specified.

3. An amusement device comprising a plurality of rotatable shafts, means for imparting rotation thereto, disks loosely mounted upon said shafts and free to move longitudinally thereof, trip members adjacent the ends of said shafts adapted to be actuated by said disks to designate the first of such disks to traverse its respective shaft, an audible signal operative upon the actuation of said trip members, disk returning means operative simultaneously therewith to move the remainder of said disks to a position in alignment with said first disk, and means adapted to be actuated, upon the completion of operation of said disk-returning means, for cutting off said audible signal and for rendering all of said means inoperative, substantially as described.

4. Amusement apparatus of the character described, comprising shafts, a prime mover for rotating said shafts, disks loosely mounted thereon and adapted to traverse same longitudinally, means operative by said disks to designate which of said disks traverses its respective shaft in advance of the remainder of such disks, means operable by said first means for preventing any of said remaining disks operating said first means, an audible signal controlled by the operation of said second-mentioned means, disk-returning means adapted to collect and return said remaining disks to a position in alignment with the first of said disks which has traversed its course along its respective shaft, and means operative upon completion of movement of said disk-returning means, for rendering all of said means idle.

5. An amusement apparatus comprising front and rear supports, shafts journaled within said supports, disks loosely carried by said shafts and freely movable longitudinally thereof, front and rear trip members, carried by the respective supports, and adapted to be actuated by said disks, means for imparting rotation to said shafts for effecting said disk movement by forces of inertia, annunciating means adapted to be operated by the first of said disks to traverse its shaft in a rearward and forward direction, by reason of consecutive tripping of rear and front trip-members, a cut-out operative upon the actuation of said annunciating means to prevent succeeding disks tripping said front trip-members, disk-returning means operative upon the completion

of movement of said first disk for returning the remaining disks to an aligned position therewith, and means adapted to be actuated upon the completion of operation of said 5 disk-returning means, for rendering all of said means inoperative and in condition for succeeding operations in similar sequences, substantially as, and for the purpose specified.

- 10 6. In an amusement apparatus of the character described, the combination of a plurality of rotatable shafts, disks loosely carried by said shafts, a motor in operative connection with said shafts, a push-button 15 in circuit with a source of electrical energy and adapted to control said motor, trip-members adjacent the front and rear ends of said shafts adapted to be actuated by said disks upon movement thereof longitudinally 20 along said shafts, annunciating means for designating the first disk which has operated both rear and front trip-members consecutively, cut-off means adapted to operate upon the tripping of said front trip-member 25 by said first disk for preventing further actuation of the remaining annunciators, a second motor, disk-returning means operable thereby for returning the remainder of said disks to a position in alignment with said 30 first disk, a pole-changer operative at this juncture to cause reverse operation of said second motor to effect the return of said disk-returning means to its normal idle position, and a throw-off unit operable upon the 35 completion of movement of said disk-returning means to render all of said means and units idle and in condition to re-execute the foregoing functions in the aforesaid sequence upon each succeeding manipulation 40 of the push-button substantially as, and for the purpose specified.

7. In a device of the character described, the combination of a plurality of rotatable shafts, front and rear supports therefor, 45 means for imparting rotation to said shafts, disks loosely mounted thereupon, trip-members carried by the respective supports

and adapted to be actuated by longitudinal movement of said disks along said shafts; an annunciator and an electro-magnetic 50 switch so arranged in an electrical circuit with said front and rear trip-members as to designate the first disk which has successively operated said rear and front trip-members, cut-out means operative simultaneously with and controlled by said electro-magnetic switch for preventing further actuation of the trip-members by the remainder of the disks, an audible signal adapted to be set into operation upon actuation of said 55 cut-out, an auxiliary propelling agency, disk-returning means operable thereby for returning said disks to an aligned position adjacent the front ends of said shafts, means operative at this juncture for cutting off 60 said propelling agency, a pole-changer, means operable upon the substantial stopping of said auxiliary propelling agency for shifting said pole-changer to a position to again start said agency in reverse operation for 65 returning said disk-returning means to its normal idle position adjacent said rear supports, throw-off means carried by said disk-returning means and adapted to be actuated thereby, when the same has substantially 70 completed its movement, for cutting off said auxiliary propelling agency and for simultaneously setting said pole-changer in condition to operate said agency in a forward direction upon succeeding operations of the 75 aforesaid units, a source of electrical energy common to all of said units, a push-button in circuit with said electrical energy for controlling said shaft rotating means, cut-off means operative upon said actuation of the 80 throw-off mechanism for rendering all of said units and devices idle and setting their respective controlling circuits in condition for re-execution of the foregoing functions upon succeeding manipulations of said push-button.

Signed at New York in the county of New York and State of New York.

WILLIAM B. WARING.
